STOCKING

Filed Aug. 4, 1931

FIG. 2.

FIG. 1.

FIG. 3.

William H. Gosch,
Inventor

By

W.H. Gosch
Attorney

UNITED STATES PATENT OFFICE

WILLIAM H. GOSCH, OF READING, PENNSYLVANIA, ASSIGNOR TO THE NOLDE AND HORST COMPANY, OF READING, PENNSYLVANIA, A CORPORATION OF PENNSYLVANIA

STOCKING

Application filed August 4, 1931. Serial No. 555,015.

This invention relates to stockings, and particularly to an improved construction of the top portion thereof characterized by a multiple-ply structure adapted to normally provide special strength and anti-run quality, in connection with capacity for increasing the length of the stocking when desired; as fully described in connection with the accompanying drawing showing a preferred embodiment of the complete invention, the novel features being clearly defined in the subjoined claims.

Fig. 1 is an elevation of the top portion of a normal length stocking embodying my invention, part thereof being a longitudinal section showing the turned-down portion secured to the body of the stocking in preferred manner.

Fig. 2 is a similar view to Fig. 1, but showing the stocking lengthened by extending up the turned-down portion of Fig. 1, after releasing the latter from its attachment to the body of the stocking.

Fig. 3 is a fragmental view indicating a convenient manner of operatively securing the free end of the removable thread which is employed to disengageably secure the turned-down portion as indicated in Fig. 1.

It is well known that the top portions of stockings are subjected in service to special strains, with resulting liability of thread breakage and runs; and that special fabric reinforcement has been heretofore resorted to for the purpose of avoiding particularly the injurious effects incident to connection of garters to these portions of the stocking. A further cause of trouble, both to dealers in and users of stockings, is incidental to variations in the lengths of stockings that are required

by different users to properly position the top portions of the applied stockings; such variation involving need of providing different-length stockings in each size, to select from, and uncertainty as to actual satisfaction in use. The present invention provides an improved top construction of perfectly symmetrical appearance, which normally avoids danger of injury thereto with resulting runs, and which also enables ready variation in length as may be required for proper

positioning of the top with relation to the leg of the wearer and the connecting garter.

Fig. 1 illustrates a preferred embodiment of the complete invention, in which the top portion A of the stocking is made up of three fabric layers, 1, 2, and 3 respectively; layers 1 and 2 of which jointly form a turned-down welt portion, while the layer 3 is a covering section of the usual body fabric B, to which the edge 4 of the down-turned portion 1-2 is secured. The primary effect of such construction is to provide a multiple-ply top A instead of the usual two-ply welt top, but having substantially the same appearance as in the ordinary stocking; and the means indicated for securing the down-turned portion 1-2 to the body fabric, comprises a removable thread 10, the withdrawal of which permits of turning outward the normally down-turned portion 1-2 so as to lengthen the stocking, as indicated in Fig. 2, when required for positioning the top properly upon the wearer.

To provide most satisfactorily for securing the down-turned portion of the stocking to the body fabric, and also for readily releasing the same to lengthen the stocking in case this is desired, registering thread-openings are formed in the stocking, at 11 adjacent the edge 4 of the down-turned portion 1-2, and at 13, 14 in the body zone 3^a to which attachment is made; said openings being conveniently made by well known picot looping, which also provides an ornamental top-edging and body zone when the stocking is lengthened as indicated in Fig. 2. While the similar looping 15 at the folding-over line provides the like ornamental top-edge indicated in Fig. 1.

The removable thread 10 which secures the down-turned top portion as indicated is engaged in said registering openings 11, 13 and 14 so as to provide an elastic chain-stitch effect which permits of required circumferential stretching of the fabric and also of easy removal by pulling upon a free end of the thread; the end of such thread being normally held in the fabric but being readily released when intended, so as to enable required pulling thereon for removing of the thread.

Fig. 3 indicates a satisfactory securing of the free end of the thread 10 employed to provide the chain-stitch connection of the turned-down portion of the stocking to the body of the latter, whereby unintended loosening of the connection is prevented while at the same time enabling ready disconnection when desired; deliberate pulling upon the interiorly exposed thread portion 10^a, serving to first release the locking loop 10^b and to thereafter withdraw the thread entirely so as to permit extending of the stocking when desired.

The down-turned portion of the top, is preferably turned inward as illustrated, so that the edge thereof is hidden, and fully as neat an appearance insured as with an ordinary two-ply top; the top-thickness provided by increasing the number of fabric layers giving increased strength for garter attachment and avoidance of runs without special reinforcement. It is to be understood that my invention is equally applicable to a stocking having a single thickness top, reinforced or not as desired. The capacity for lengthening the stocking when desired insures proper locating of the top upon the leg of the wearer. The particular means set forth for securing the down-turned top may also be modified with like results as to convenient disengagement when desired and avoidance of runs, without departing from the invention as defined in the claims.

What I claim is:

- 35 1. An extensible stocking having a finished-edge top portion, and an adjacent body portion formed with a row of enlarged openings below said top portion, said top portion being turned down and secured to said body portion by a removable thread extending through said top portion and the openings in the body portion.
- 40 2. An extensible stocking having a finished double-ply welt turned down upon the adjacent single-ply body portion of the stocking and detachably secured to the latter by means of a removable attaching thread extending through registering apertures knitted into said welt and body portion.
- 45 3. An extensible stocking having a top portion formed with enlarged openings, and a body portion formed with a plurality of rows of enlarged openings below said top portion, said top portion being turned down on the adjacent body portion and detachably secured thereto by a removable attaching thread extending through said openings in said top portion and the openings of said rows in said body portion.
- 50 4. The method of making an extensible stocking having a turned welt top portion, which comprises knitting registering series of openings in the inner and outer walls of the welt below the folded edge thereof, knitting a corresponding series of openings in the

body portion of the stocking below the welt, turning down said welt upon the adjacent body portion of the stocking to bring said openings in the welt into register with said openings in the body portion, and detachably securing the turned down welt to the body portion by means of a draw thread engaged in said registering openings.

In testimony whereof, I affix my signature.

WILLIAM H. GOSCH.
